BRASSIÈRE WITH IMPROVED STAY MEANS

Benjamin H. Mixon, Roswell, N. Mex.

Application March 18, 1947, Serial No. 735,453

2 Claims. (Cl. 2—42)

1

This invention relates to certain new and desirably useful improvements in brassières and has particular reference to practical ways and means for stiffening and staying predetermined median portions, transversely considered, and in a manner to insure smooth fitting maintenance at all times.

Ordinary brassières embody a body embracing band whose rear ends are interconnected by separable fasteners, the central portion having spaced breast cups and an intervening form fitting front-piece, generally a wedge-shaped web. The side-reaches (sometimes described as tapering wings) of said band, from points just outwardly of said cups to the rear connectable terminals tend, when in use, to rumple and wrinkle, thus permitting the wearer's breasts to sag, regardless of cup styling and perfected construction. This unsightly breakdown of a brassière is usually traceable to the "upriding" lower edges of said wings, for in use there is a constant tendency for such edges to "creep" up, whereby to ruin the intended form fitting and restraining purposes of the garment.

For some time now there has existed a constant public demand for an available brassière so constructed as to be free of the stated objections; which accounts for the instant invention, an adaptable and desirable improvement which not only achieves the corrective ends sought, but also satisfies other requirements of the trade such as simplicity, adaptability, durability, appropriateness and conforming comfort to the wearer.

In addition a brassière having so-called "uplift" and form sustaining features within the vicinity of the breast cups is a feature of finesse likewise desired by the discreet wearer. It follows, therefore, that it is an object of the invention to adapt and use stiffening and staying means but to so arrange and situate same that it applies the principle of reinforcement where best usable and applicable to constantly maintain the form fitting characteristics not only of the breast cups but also of the remainder of the garment.

More specifically, and in carrying out the principles of the invention, best results are had through a preferred embodiment of such means wherein the latter is characterized by carefully shaped and located pockets, these to contain readily insertable and removable stays so as to insure constant existence of the shape sustaining characteristics while, at the same time, permitting the garment to be handily washed and ironed without interference from said stays.

2

Other objects and advantages will become more readily apparent from the following description and the accompanying illustrative drawings.

In the drawings, wherein like reference numerals are employed to designate like parts throughout the views:

Figure 1 is a perspective view of a fragmentary type showing a brassière embodying the features of this invention and illustrating the manner in which it is worn and the indicated results attained;

Figure 2 is an enlarged fragmentary elevational view of one of the wing-like end portions, this revealing to advantage the specific adaptation of the instant invention;

Figure 3 is a longitudinal section on the plane of the line 3—3 of Figure 2, looking in the direction of the arrows;

Figure 4 is a perspective view of the insertable and removable stay per se, and

Figure 5 is a detail perspective view stressing the delineation of the pocket, particularly the mouth of said pocket.

Referring now to the drawings by distinguishing reference numerals, it will be seen that the brassière, in all general appearances, conforms to what one might visualize as a conventional type. It is of any suitable material and includes a body encircling and embracing member or band 6 which is partly held in place by shoulder straps 7. The front portion of the brassière, the part denoted generally by the numeral 8 is made up principally of suitable breast cups 9 and 10 these having an intervening wedge-shaped web 11 therebetween, as usual. The rearwardly directed and side and back embracing end portions or so-called "wings" are denoted by the numerals 12 and have their coacting ends separably connectable together in any common fashion (not shown). The wings 12 have customary marginal bindings 13 and 14 of stitched form and this too is of customary formation.

The essence of this invention is exhibited in the drawings as incorporated and confined within the limits of the wing-like reach 12. By this, it is meant, that the structure 12 is reinforced with added fabric and is also stabilized by way of stiffening and stay means for transverse strengthening purposes. Broadly, the means chosen comprises a pocket with an insertable and removable stay normally located in said pocket. The pocket is here generally denoted by the numeral 15 (see Figure 2). It is narrow at its lower end and wide at its upper end and is defined primarily by rows of stitching 16 transversely and arcuately ex-

tending across the part 12, additional rows of stitching 17 being arranged on an opposite side and said stitching 17 being straight across, that is, at approximate right angles to the longitudinal dimension of said part or reach 12. The binding 14 along the bottom of the pocket serves to close said bottom and it will be noted that this bottom denoted at 18, is relatively narrow. At the top, the stitchings 19 forming a part of the binding 13 terminate at the point 20 where they serve to define a relatively small mouth 21 to permit the plastic or other splint or stay 22 to be inserted and removed. By making the mouth of the pocket off-center or to one side, the stay is inserted somewhat diagonally and removed in the same manner. When once it is lodged in the pocket it is confined in the left-hand end portion only, that is, between the narrow lower portion 18, the stitchings 17 and the stitchings 19 at right angles to the stitchings 17. In actual side elevation, the stitchings which go to define or delineate the shape of the pocket, the latter resembling a "holster."

I desire to emphasize the fixed form shaping results attainable through the use of a pocket and stay of the type shown and described but call attention to the fact that other equivalent stiffening and staying means might well be employed. Also, and in connection with Figure 3, I call attention to the fact that on the interior the pocket is reinforced by an added or extra ply as at 23, this being stitched to the outer ply 24 which, with the remaining ply 25, goes to make up a double thickness reach 12. Thus, the pocket has a small laterally disposed mouth and is reinforced, this providing an arrangement which guards against accidental displacement of the stay once it is lodged in place, but which permits removal of the stay, the pocket itself being sufficiently strong to withstand continual insertion and removing of said stay. It is necessary to bodily remove the stay to facilitate washing the brassiere, obviously.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and arrangement of parts may be resorted to in actual practice so long as no departure is made from the invention as claimed.

What I claim is:

1. A brassière for everyday use comprising an endless-type body encircling and restraining band characterized by a frontal portion having customary breast cups and complemental gradually and rearwardly narrowing wing-like end portions, the terminals of said end portions being separably connectable, said wing-like end portions at points adjacent to the respective breast cups each having a stay receiving and retaining pocket, said pocket extending transversely from the upper to the lower edge portion of the band, being relatively narrow and closed at its lower end portion and gradually widening toward its upper end portion, the wider upper end portion of the pocket being closed except for a limited opening and the latter providing a small entrance and exit mouth, and stays lodged in the completely closed portions of the respective pockets, said stays, when canted within the respective pockets being susceptible of removal by way of the small mouths.
2. A brassière for regular everyday use comprising a body encircling and restraining band including a frontal portion having customary breast cups and wing-like rearwardly narrowing end portions, said end portions, at points adjacent to the respective breast cups being provided with pockets, each pocket being stitched around marginal edge portions, being narrow at one end and wide at the other end and of holster-like form, a stay fitted into each pocket, the stay being of a cross-section to fit snugly in the restricted end of the pocket, the opposite wider end of the pocket having a restricted slot forming a mouth and said mouth being slightly larger than the cross section of the stay to allow the latter to be inserted into the pocket by way of said mouth and subsequently removed from the pocket by way of said mouth in the manner and for the purposes described.
